UNITED STATES PATENT OFFICE.

WHITMAN PRICE, OF MOUNT OLIVE, NORTH CAROLINA.

COTTON-CHOPPER.

SPECIFICATION forming part of Letters Patent No. 317,195, dated May 5, 1835.

Application filed January 23, 1885. (No model.)

To all whom it may concern:

Be it known that I, WHITMAN PRICE, of Mount Olive, in the county of Wayne and State of North Carolina, have invented certain new and useful Improvements in Cotton-Choppers; and I do hereby declare that the following is a full, clear, and exact description of the invention, which will enable others skilled in the art to which it appertains to make and use the same, reference being had to the accompanying drawings, which form a part of this specification, and in which—

Figure 1 is a side view of my improved cotton-chopper. Fig. 2 is a longitudinal vertical sectional view of the same. Fig. 3 is a transverse sectional view taken through the axle of the machine, and Fig. 4 is a detail view. Fig. 5 is a top plan view, and Fig. 6 is a bottom plan view, of the machine.

20 The same letters refer to the same parts in all the figures.

This invention relates to that class of devices which are known as "cotton-choppers," and it has for its object to produce a device of this class which shall possess superior advantages in point of simplicity, durability, ease of operation and manipulation, and general efficiency.

With these ends in view the invention consists in the improved construction and arrangement of parts, which will be hereinafter fully described, and particularly pointed out in the claims.

In the drawings hereto annexed, A designates a frame of suitable construction provided with boxes or bearings B B for a transverse shaft or axle, C, carrying a transporting-wheel, D, and provided with a bevel-gear, E, engaging a pinion, F, mounted upon the forward end of the longitudinal shaft G, which latter is journaled in the main frame, and to which a rotary motion is thus imparted. The rear end of the shaft G carries the hub H, in which the radial arms or stems I I are mounted, each of the latter being provided at its outer end with a transverse knife or cutter, which, on the revolution of the shaft G, serves the purpose of cutting or chopping the young cotton-stalks as the machine passes over the field, in the usual manner. To this portion of

the invention it will not be necessary to call further attention, inasmuch as it will not be herein claimed.

The frame proper, which consists mainly of two vertical parallel side pieces, square, or nearly so, is provided at its lower end with V-shaped brackets K K, the lower ends or corners of which are provided with shoes or runners L L arranged pivotally, so as to insure freedom of motion whenever the ground is touched. The shoes L are provided with pins L', passing through perforations in them, and the said pins may bear against the rear edges of the forward arms of the brackets K when the runners are running flat upon the ground, allowing the drive-wheel to touch the ground; or they may bear against the rear edges of the rear arms of the brackets when the runners are in their upright positions, raising the drive-wheel off the ground, the first-described position being shown in Fig. 1 and the last-described position being shown in Fig. 2. Handles M M are attached to the front portion of the upper end of the frame, and to uprights N N at the rear end of the latter, so as to enable the machine to be conveniently manipulated.

Mounted upon the transverse main shaft or axle C are a pair of arms or bars, O O, extending forwardly and joined so as to form a tongue or draft-pole, P, which is, in practice, to be provided with a clevis or link, to which the draft may be attached. The front ends of the arms or bars O O are provided on their inner adjoining sides with recesses Q Q of a segmental shape, and having teeth R R to receive and retain a segmental toothed bar, S, extending upwardly from the front end of a yoke, T, mounted upon the axle C within or between the draft-bars O O. At the junction of the bar S with the yoke T is pivoted a shoe or runner, U, acting in substantially the same manner as the runners L L, to which reference has hereinbefore been made.

The upper front end of the draft-pole, composed of the arms O O, is provided with a rope or chain, V, extending rearwardly to some portion of the frame within easy reach of the handles, and where a hook or other device is provided, to which it may be readily attached.

From the foregoing description, taken in connection with the drawings hereto annexed, the operation and advantages of this invention will be readily understood.

5. The construction of the machine is simple in the extreme, and hence inexpensive and not liable to get out of order.

In guiding the machine over the ground the runners, which are arranged to support both to the front and rear ends of the machine, as occasion shall require, will cause it to run easily and without the exercise of excessive power on the part of the draft-animal or the operator, while by simply raising the draft-bar by means of the chain V, and by placing the runners L in their upright position, the frame may be raised so as to throw the machine out of gear by raising the drive-wheel out of contact with the ground.

20. Having thus described my invention, I claim and desire to secure by Letters Patent of the United States—

1. In a cotton-chopper, a frame mounted upon a wheel, D, and having V-shaped brackets having pivoted shoes or runners, substantially as and for the purposes herein set forth.

2. In a cotton-chopper, a frame mounted upon a wheel, D, and having V-shaped brackets having pivoted shoes or runners at their lower corners, in combination with a pivoted draft-bar connected adjustably with an arm having a pivoted shoe or runner supporting the front end of the machine, substantially as and for the purpose herein set forth.

3. In a cotton-chopper, the combination of 35 a frame, a transverse main shaft or axle having a bevel-gear, a longitudinal shaft having a pinion engaging said bevel-gear and provided at its rear end with a hub having radial arms provided with cutters, two pivoted runners supporting the main frame, and an adjustable draft-frame having a pivoted shoe or runner supporting the front portion of the frame, substantially as and for the purposes herein set forth. 40 45

4. In a cotton-chopper, the combination of a frame, supporting brackets having pivoted runners, a transverse main shaft, a bifurcated draft-beam journaled upon the latter and having a toothed recess at its front end, a yoke 50 journaled upon the main shaft within the draft-beam and having a segmental bar at its front end, connected adjustably with the front end of the draft-beam, and a shoe or runner pivoted at the junction of the yoke with its 55 segmental bar, and a chain for adjusting the draft-bar and yoke with the front runner, substantially as and for the purpose herein set forth.

5. In testimony that I claim the foregoing as 60 my own I have hereunto affixed my signature in presence of two witnesses.

WHITMAN PRICE.
